(57) **CLAIM**

The ornamental design for a multifunctional storage stand, as shown and described.

DESCRIPTION

FIG. 1 is a front and top perspective view of a multifunctional storage stand showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom perspective view thereof.

FIG. 9 is an enlarged detail view of a stand of the multifunctional storage stand, taken from the circle part "9" in FIG. 8; and,

FIG. 10 is an enlarged detail view of a knob of the multifunctional storage stand, taken from the circle part "10" in FIG. 8.

The broken lines in the top plate depict portions of the multifunctional storage stand and form no part of the claimed design. The broken line circles and lead lines in FIGS. 8-10 depict reference to the enlarged detail views and do not form part of the claim.

1 Claim, 10 Drawing Sheets
